PRESSING MACHINE TAIL CLAMP

Otto H. Pearson, Salt Lake City, Utah, assignor
to Louis N. Strike, Salt Lake City, UtahOriginal application April 2, 1945, Serial No.
586,053. Divided and this application Decem-
ber 12, 1946, Serial No. 715,687

7 Claims. (Cl. 38—12)

1 This invention relates to pressing machines and deals more particularly with a clamping mechanism for the tail of a shirt being pressed in said machine. This application is a division of my co-pending application entitled Shirt pressing machine, Serial Number 586,053 and filed April 2, 1945.

The above co-pending application discloses a machine provided with two bucks mounted on a hollow revoluble column, one on either side thereof, for alternate positioning of said bucks with respect to a pressing head, whereby the bosom or front portion of a shirt draped over each buck is pressed between said pressing head and the shirt draped buck. Steam for the pressing operation is admitted to the pressing head and also to the bucks through said hollow column.

The present invention has for its primary object to provide improved and simple shirt tail clamping means whereby a shirt on the buck is held smooth and taut for a ceaseless pressing operation.

Another object of the invention is to provide shirt tail clamping means which is manually operable to clamp a shirt on a buck, which remains clamped during a pressing operation, and which automatically releases during movement of the shirt draped buck from pressing position to shirt replacing position.

Another object of the invention is to provide shirt tail clamping means as indicated in which the clamp member is centrally positioned with respect to the edge facings of a shirt front to thereby clamp and engage both said edge facings and securely clamp the shirt.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a broken elevational view partly in vertical section of a support column mounting a pair of oppositely disposed bucks embodying the present shirt tail clamping means, the view

showing only one buck, the other being identical.

Fig. 2 is a vertical sectional view as taken on the line 2—2 of Fig. 1.

Fig. 3 is a broken perspective view of a clamp element employed in the invention.

Fig. 4 is fragmentary plan sectional view, to a reduced scale, showing the operative relationship between cam and toggle means employed in the invention.

The shirt tail clamping means which is illustrated comprises, generally, a support member, in this case, a hollow column 5, a pair of bucks 6 fixedly mounted on the column, one on either side thereof, a clamp element 7 extending through each buck and movable to clamp or release a shirt draped on each buck, and means 8 including fixed cam means 9 for effecting release of the clamp element 7.

The column 5 is mounted for rotation, in the direction of the arrow 10, on a circular base 11 which is rotatable by suitable means through the medium of a belt 12. A fixed base support 13, which, through the medium of a bracket 9^a, carries the cam means 9, rotationally mounts the base 11 and column 5 for rotation on means such as bearing balls 14. The column 5 is hollow for the passage of steam therethrough and has lateral connections 15 directing said steam to the bucks 6. A suitable bracket 16, spaced along the column from the connections 15, laterally extends therefrom to connect to each buck and thereby hold the same rigid on the column. The center line 17 is the axial center of the column and, as indicated, the present device is symmetrical on said center line with a buck 6 on each side thereof.

Each buck 6 comprises a hollow chest 18 of a shape suitable to receive and support a garment such as a shirt, the interior 19 of the chest receiving steam from the connection 15 and transmitting said steam, through suitable perforations 20, to a pad 21 on the outer face of the buck. In the present instance, centrally of each width of the buck and suitably located with respect to its upper and lower ends, there is provided a transverse passage 22 through which the clamp element 7 extends.

Each clamp element 7 comprises a plunger rod 23 extending through the passage 22, a grooved spool 24 on the inner end of the rod 23, a clamping blade 25 on the outer end of said rod, and means 26 effecting a quarter rotation of the rod and consequently, of the blade. The latter means, simply, consists of a helical groove 27 in the rod 23 and a stationary finger 28, in this

case carried by a wall of the chest 18, engaged in said groove, whereby longitudinal movement of the rod will cause the mentioned quarter rotational movement of the blade 25.

The means 8 comprises a mounting plate 29 secured to the inner face of each buck 6 and over center toggle means 30 carried by said plate and associated with the cam means 9. The plate 29 is provided with inwardly extending ears 31 for a pivot 32 supporting a toggle arm 33. A second pair of ears 34 on said plate 29 mount a rotary pins 35 through which transversely extends a toggle link 36 pivotally connected at 37 to the upper end of the arm 33. A compression spring 38 around the link 36 is confined, endwise, between said pin 35 and a shoulder 39 on the pivoted end of said link. The upper end of the arm 33 is forked as at 40 for the pivot 37 and also to accommodate the spool 24. A pair of pins 41 extend from the bifurcations of the fork into the groove of the spool to effect rotational connection of the element 7 and the toggle means 30. It is obvious that the toggle 30 has two positions to, correspondingly, hold the blade 25 against or spaced from the outer face of the buck pad 21.

The lower free end of the arm 33 carries a roller 42 designed to engage the inner face of the cam means 9 to move the arm 33 from the full to the dot-dash line positions shown during rotation of the column in the clockwise direction of arrow 10.

In operation, a garment such as a shirt S is draped over one buck 6 so that the front edge facings 43 of said garment extend vertically along the outer face of the buck pad 21 on either side of the blade 25. The normal position of the latter is vertical as shown by the dot-dash lines and outwardly spaced from said pad. The shirt facings can now be pulled into place, side by side, and held with one hand as the other is used to press the blade 25 rearwardly. The groove 27 now becomes effective to rotate the blade, the toggle spring 38 is compressed as a dead center position of the toggle is approached, and said spring becomes effective to draw the rotating blade firmly against the shirt facings 43 and press them smoothly against the pad 21. The blade 25 is now transversely disposed and, therefore, has an effective clamping hold on said shirt facings.

The machine is then operated to rotate the column 5 and to bring the shirt draped buck into pressing register with a pressing head (not shown). This rotation will bring the other buck 6 into position to receive a shirt S in the manner above set forth. During the mounting of the latter shirt, the previously mounted shirt is being pressed by the introducing of steam to the chest 18 and to the pressing head.

The machine is then again operated to rotate column 5 in the same direction of rotation. Now, as the roller 42 encounters cam means 9, the arm 33 of the toggle 30 is moved from the full line position to the dot-dash line position, effecting outward and quarter rotational movement of the clamping blade 25 and, therefore, release thereby of the shirt facings 43. The pressed shirt S is then removed and replaced by one to be pressed. The operation continues as above.

While I have illustrated and described what I now regard as the preferred embodiment of my invention, the construction is, of course, subject to modifications without departing from the spirit and scope of my invention. I, therefore, do not

wish to restrict myself to the particular form of construction illustrated and described, but desire to avail myself of all modifications that may fall within the scope of the appended claims.

Having thus described by invention, what I claim and desire to secure by Letters Patent is:

1. Mechanism of the character described comprising a movable buck for receiving a garment to be pressed, a clamp element extending through the buck movable therewith and including a clamping member manually movable to clamp portions of said garment, mechanical means connected to and movable with the clamp element, and stationary means engageable with the mechanical means for effecting release of the clamp member.

2. Mechanism of the character described comprising a movable buck for receiving a garment to be pressed, a clamp element extending through the buck movable therewith and including a clamping member manually movable to clamp portions of said garment, mechanical means connected to and movable with the clamp element, and stationary means engageable with the mechanical means for effecting release of the clamp member, said mechanical means comprising an over center spring toggle for holding the clamp element in moved position, and said stationary means comprising a cam for operating the toggle to move the clamp member to release position.

3. In mechanism of the character described, a buck, an elongated clamp plate associated with the front face of said buck, means guiding said clamp plate for bodily movement toward and from a buck, and means for rotating the clamp plate during the latter movement between a spaced aligned position with the face of the buck and an engaged transverse position with respect thereto.

4. In mechanism of the character described, a buck, an elongated clamp plate associated with the front face of said buck, an elongated support for the clamp plate, said clamp plate and support being movable along the axis of the latter, towards and from said buck, and means for rotating the clamp plate during said axial movement between a spaced aligned position with the face of the buck and an engaged transverse position with respect thereto.

5. In mechanism of the character described, a buck having a passage therethrough, an axially movable rod in the passage, means for rotating the rod during axial movement thereof, and a clamp member on the rod and associated with the buck to spirally move toward and from the buck during the mentioned movement of the rod.

6. In mechanism of the character described, a buck having a passage therethrough an axially movable rod in the passage, means for rotating the rod during axial movement thereof, a clamp member on the rod and associated with the buck for manual spiral movement toward the buck during endwise movement, in one direction, of the rod, spring toggle means for holding said rod in moved position, and means for operating the toggle means to move the rod in the other direction to spirally move the clamp member away from the buck.

7. In a garment pressing machine, a pressing buck element for a garment to be pressed, an elongated clamp mounted to be turned from a releasing position lengthwise of the buck to a clamping position crosswise of the buck and return, over-center, snap-acting spring means on the back of the buck, a helically movable plunger

70

extending through the buck and connecting the clamp on one side of the buck with the spring means on the opposite side of the buck, the spring means at one side of dead center being arranged to tend to move the clamp to a clamping position and at the other side of dead center being arranged to tend to move the clamp to a garment releasing position, a relatively stationary part of the buck and the plunger having helical groove and engaging pin means arranged to effect the turning movement of the plunger and clamp when the spring means is going from one position to the other, a pressing head element, and mechanism connected to move one of said elements to a pressing position with relation to the other element.
